UNITED STATES PATENT OFFICE.

ELIJAH WINDSOR, OF OIL CITY, ONTARIO, CANADA.

HOOP-PLANER KNIFE.

SPECIFICATION forming part of Letters Patent No. 355,580, dated January 4, 1887.

Application filed September 28, 1885. Serial No. 178,470. (No model.)

To all whom it may concern:

Be it known that I, ELIJAH WINDSOR, a British subject, residing at Oil City, in the county of Lambton, in the Province of Ontario, 5 Dominion of Canada, have invented new and useful Improvements in Hoop-Planer Knives, of which the following is a specification.

My invention generally relates to that class of knives that are used in rotary heads for 10 planing hoops or similar articles, and particularly relates to that class of knives that plane the principal surface of the object, and at the same time shape the corners or edges.

My invention therefore consists of constructions and combinations, all as will hereinafter 15 be described in the specification, and pointed out in the claims, reference being had to the accompanying drawings, in which—

Figure 1 represents a front elevation of a 20 planer-knife embodying my invention; Fig. 2, a rear elevation of the knife shown in Fig. 1; Fig. 3, a longitudinal section, and Fig. 4 a transverse section on line xx .

A represents the body of the knife, having 25 the curved edge a and lips a' . The outer edges, a^2 , of the front side of the knife are beveled at a^3 from the lips a' to about half-way the length of the knife. This beveling gives

a cutting-edge to the lips a' when they come in contact with the material to be planed. 30

The back of the knife is provided with the depression or recess a^4 , which reduces the thickness of the blade at that point, and consequently the time and labor required to regrind the knife. 35

I am aware that bits have been provided with cutting-edges at both ends and grooves on the front and back, so that the bit may be reversed and used either for cutting a tenon or groove, and that the cutting-edges of knives 40 have been grooved to lighten the same, and these I do not claim; but

What I do claim is—

1. A hoop-planer knife having the cutting-edge a , the lips a' , and the beveled edges a^3 45 on the front of the knife, and extending to about midway of the length of the latter, substantially as described.

2. A hoop-planer knife having the cutting-edge a , the lips a' , the beveled edges a^3 on the 50 front of the knife, and the recess a^4 on the back of the knife, substantially as described.

ELIJAH WINDSOR.
